Fig. 3.

This technical drawing shows a cross-section of a composite structure. At the top, a thick, rectangular base layer is labeled with the number 4. A vertical, lighter-colored column is labeled with the number 5. A horizontal, ribbed band, labeled with the number 12, is attached to the side of the vertical column. A horizontal band, labeled with the number 14, is attached to the bottom of the vertical column. A small, curved bracket labeled with the number 3 is attached to the bottom of the vertical column. The bottom edge of the structure is irregular and wavy.

UNITED STATES PATENT OFFICE.

JOSEPH V. RICHARDSON, OF GOSHEN, INDIANA.

GROOVING AND EQUALIZING MACHINE.

1,243,663.

Specification of Letters Patent. Patented Oct. 16, 1917.

Application filed March 15, 1915. Serial No. 14,548.

To all whom it may concern:

Be it known that I, JOSEPH V. RICHARDSON, a citizen of the United States, residing at Goshen, in the county of Elkhart and 5 State of Indiana, have invented a new and useful Grooving and Equalizing Machine, of which the following is a specification.

By way of explanation it may be stated that as is common and well known, the 10 stiles of step-ladders are provided intermediate their ends with a plurality of transverse grooves which receive the steps. Further, the stiles are cut off at their ends otherwise than at a right angle to the length of 15 the stiles, so that the stiles at their lower ends will coöperate properly with a support when the stiles are inclined and to the end that the upper extremities of the stiles may, if desired, receive a top plate, the top plate 20 standing in a horizontal position when the stiles are inclined.

One object of the present invention, in view of the foregoing is to provide a machine which, in a single operation, will cut 25 all of the grooves in the stiles to receive the steps and trim off the ends of the stiles at an acute angle to the length of the stiles.

It is within the scope of the invention to provide novel means for retaining the stiles 30 in place while the same are being grooved and cut; to improve the driving mechanisms whereby movable parts are actuated; to provide means whereby, at the will of the operator stiles may be trimmed off at their ends 35 without cutting grooves in the stiles; and, generally, to improve and to enhance the utility of devices of that type to which the present invention appertains.

With the above and other objects in view 40 which will appear as the description proceeds, the invention resides in the combination and arrangement of parts and in the details of construction hereinafter described and claimed, it being understood that changes 45 in the precise embodiment of the invention herein disclosed can be made within the scope of what is claimed without departing from the spirit of the invention.

In the accompanying drawing:—

- 50 Figure 1 is a top plan;
Fig. 2 is a rear end elevation;
Fig. 3 is a side elevation;
Fig. 4 is a fragmental front elevation showing the means whereby the table is 55 raised and lowered;

Fig. 5 is a fragmental vertical sectional detail taken through one of the grooving cutters;

Fig. 6 is a side elevation showing the product which the machine is adapted to turn 60 out.

In order to facilitate the description and in order that a clear understanding of the structure may be obtained, that end of the device to which the reference character A is 65 applied in Fig. 3 may be denominated the front end of the machine, the rear end of the machine being designated by the reference character B.

In carrying out the present invention there 70 is provided a supporting frame of any desired form and denoted generally by the numeral 1. Located above the frame 1 and connected thereto by hinges H is a table 2. Screws 3 are threaded into extensions 4 constituting 75 a part of the supporting frame 1, the upper ends of the screws 3 bearing against wear plates 5 which, as shown in Fig. 4, are carried by the table 2 adjacent the forward end thereof. By manipulating the screws 3, the 80 free end of the table may be raised and lowered for a purpose which will be described fully hereinafter, but at this place it may be stated briefly that the function of the screws 3 in raising the table 2 is to permit the ends 85 of the stiles of a step-ladder to be cut off at an angle, without grooving the stiles to receive the steps.

Journalized for rotation in the supporting frame 1 near to the rear, lower portion 90 thereof is a drive shaft 6 which, as shown in Fig. 2, extends entirely across the frame, the drive shaft being held for rotation in bearings 7. Any suitable means may be provided for rotating the shaft 6 but in the 95 present instance, the same carries at one end, fixed and loose pulleys 8 appearing clearly in Fig. 1. Secured to the shaft 6 is a pulley 9 about which is trained a belt 10, the belt being passed about a pulley 11 secured 100 to a relatively short transverse shaft 12 journaled, as shown in Fig. 4, in a bearing 14 carried by the supporting frame 1 near to the upper forward corner thereof as will be understood from Fig. 3. The shaft 12 carries, within the contour of the supporting frame 1, a pulley 15 about which is trained a belt 16, the same being extended downwardly and being passed around a pulley 17 105 secured to a shaft 18 journaled on the sup- 110

porting frame 1 near to the lower forward portion thereof. Attached to the shaft 18 is a sprocket wheel 19 about which is trained a slack sprocket chain 20 engaged with a sprocket wheel 21 secured to a shaft 22 journaled for rotation in the vertically adjustable table 2 near to the forward end of the table. The shaft 22 extends entirely across the table 2 as shown in Fig. 1, and secured to the shaft 22 intermediate its ends are sprocket wheels 23 carrying slack conveyer chains 24 provided with upstanding fingers 41. The conveyer chains 24 are passed about sprocket wheels 25 carried by a shaft 26 journaled in the rear portion of the table 2. A skilled mechanic will understand that the shaft 26 may rotate with the sprocket wheels 25, or the sprocket wheels 25 may rotate on the shaft 26, the latter being fixed. In connection with the conveyer chains 24, it is to be observed that the table 2 is of a longitudinally slatted construction so that the chains 24 and their fingers 41 may exercise their proper functions with respect to the material which is being worked upon.

At this point, the description of the machine may properly be suspended to permit an examination of the product.

In Fig. 6 of the drawings, one stile of a step-ladder is shown and denoted by the numeral 27. The beveled ends of the stile 27 appear at 58, and the step-receiving grooves in the inner face of the stile are shown at 59.

The stile 27 is laid on the table 2, as shown in Fig. 1 and is engaged by certain of the fingers 41 on the conveyer chains 24, the stile-engaging fingers 41 being so selected by the operator that the length of the stile 27 is not disposed at right angles to the conveyer chains 24. If the stile 27 be now advanced from the front of the machine toward the rear end thereof, and if suitable mechanism is provided, the ends of the stile 27 will be trimmed off on a bevel, as indicated at 58.

The driving train whereby the conveyer chains 24 are actuated embodies the shaft 6, the pulley 9, the belt 10, the pulley 11, the shaft 12, the pulley 15, the belt 16, the shaft 18, the sprocket wheel 19, the sprocket chain 20, the sprocket wheel 21, the shaft 22 and the sprocket wheels 23. By means of the driving train above described, when the conveyer chains 24 are actuated, the fingers of the conveyer chains will advance the stile 27 in the inclined relation shown in Fig. 1, thus to define the angles at which the bevels 58 are formed.

The mechanism whereby the ends of the stiles 27 are cut as shown at 58 will now be described.

Carried by the table 2 adjacent the sides thereof are upstanding brackets 28 supporting a cross bar 29 which may be in the form

of a channel beam. Hand screws 30 rotate in the upper flange of the cross bar 29 and bear against the lower flange thereof as Fig. 3 will show. Mounted upon the hand screws 30 to traverse the same vertically are nuts 31 formed at the forward ends of rearwardly extended arms 32 in which a transverse saw shaft 33 is journaled. Mounted upon the saw shaft 33 are end saws 34 which serve to cut the bevels indicated at 58. In order that the stiles 27 may be cut to different lengths, the end saws 34 are adjustable toward and away from each other on the saw shaft 33, and with this end in view, the saws 34 are provided in their hubs with set screws 35 adapted to engage the saw shaft. In order to secure a rotation of the saw shaft 33, the same is provided at one end with a pulley 36 about which is trained a belt 37 passed about a pulley 38 secured to one end of the drive shaft 6.

A means is provided whereby the stile 27 is held down while the same is being cut terminally by means of the saws 34 and while the stile is being grooved as shown at 59 by a mechanism to be described hereinafter. The mechanism for holding down the stile 27 embodies guides 39 formed upon or attached to the cross bar 29. The guides 39 are provided with set screws 40 adapted to engage uprights 42 vertically adjustable in the guides, the uprights 42 being provided at their lower ends with bearings 43 in which is journaled for rotation a roller 44, the roller being adapted to engage the stile 27 while the same is being operated upon.

A means is provided for guiding the stile 27 with respect to the table 2 and, to some extent, for holding down the stile 27 upon the table. This mechanism comprises a pair of upright standards 45 attached to the table 2 as shown in Fig. 3, bearings 46 being yieldably mounted upon the standards 45 for vertical movement. Threaded onto the upper ends of the standards 45 are nuts 47, compression springs 48 being interposed between the nuts 47 and the bearings 46, a roller 49 being journaled in the bearings. The roller 49 is yieldably pressed against the stile 27 by the action of the springs 48 and the compressive effect of the springs may be adjusted by means of the nuts 47.

The mechanism whereby the grooves 59 are formed in the stile 27 embraces a shaft 50 extended transversely of the supporting frame 1 and journaled in bearings 64 thereon. Attached to the shaft 50 are any desired number of cutters 51 located below the roller 49. The cutters 51 may be variously formed but, as indicated in Fig. 5, they may comprise side plates 52 having teeth 53, the side plates being connected by transverse knives 54. The cutters 51 serve

to fashion the grooves 59 in the stiles 27. The shaft 50 is provided with pulleys 55 engaged by belts 56 trained around pulleys 57 on the drive shaft 6, the drive shaft thus 5 constituting a means whereby the shaft 50 and its cutters 51 are rotated.

At times it may be desirable to cut off the ends of the stile 27 as shown at 58, without fashioning the grooves 59. Under 10 such circumstances, the screws 3 are manipulated, the table 2 being raised until the upper surface thereof is above the upper portions of the grooving cutters 51. Then, as the stile 27 is advanced by the conveyer 15 chains 24, the end saws 34 alone will act, the stile emerging from the machine with its ends beveled as shown at 58 the grooves 59 being absent.

The front roller 44 may be raised and 20 lowered by loosening the set screws 40 which engage the uprights 42. Projecting rearwardly from the cross bar 29 are horizontal arms 60 to the rear ends of which are attached adjustably, vertical bars 61, the latter preferably being provided with vertical slots 62 receiving adjustably bolts 63 or like clamping means mounted in the arms 60. The bars 61 carry at their lower ends, 25 shoes 61^a which serve to hold down the 30 product while the same is being operated upon as hereinbefore described.

From the foregoing it will be obvious that there is disclosed in this application a simple mechanism whereby in a single operation, the ends of the stiles 27 may be cut off diagonally as shown at 58 and whereby the grooves 59 may be formed, it being possible, at the will of the operator to make the end cuts indicated at 58, without grooving the stiles as shown at 59.

As will be understood readily, the hand

screws 30 are employed for raising and lowering the end-trimming saws 34.

The supporting frame 1 and the table 2 may be described under the general design 45 nation of a "support".

Having thus described the invention, what is claimed is:—

1. In a machine for end-trimming and grooving ladder stiles, a frame; a stile-supporting table vertically adjustable with respect to the frame; a substantially horizontal shaft journaled on the frame; stile-grooving cutters carried by the shaft; a second shaft supported for rotation on the table independently of the frame; end trimming saws carried by the second shaft, the second shaft being disposed above the table to locate the axis of rotation of the end-trimming saws above the table; means for raising the table to render the end-trimming saws alone operative; and means carried by the table for feeding stiles with respect to the saws and the cutters.

2. In a machine for end-trimming and grooving ladder stiles, a supporting frame; a work-supporting table pivotally assembled with the frame for vertical adjustment; work feeding means coöperating with the table; a grooving cutter carried by the frame; an end-trimming saw carried by the table and means coöperating with the table to raise the same, thereby to render the end-trimming saw alone operative.

In testimony that I claim the foregoing 75 as my own, I have hereto affixed my signature in the presence of two witnesses.

JOSEPH V. RICHARDSON.
